UNITED STATES PATENT OFFICE.

JAMES G. AGNEW AND REED K. POND, OF ANNAPOLIS, MARYLAND, ASSIGNEES, BY MESNE ASSIGNMENTS, TO FREDERICK L. OLMS TED, TRUSTEE, OF ANNAPOLIS, MARYLAND.

DESIGN FOR A BADGE OR SIMILAR ARTICLE.

Application filed September 13, 1924. Serial No. 10,767. Term of patent 3½ years.

To all whom it may concern:

Be it known that we, JAMES G. AGNEW and REED K. POND, both citizens of the United States, residing at Annapolis, in the county of Anne Arundel and State of Maryland, have jointly invented a new, original, and ornamental Design for a Badge or Similar Article, of which the following is a specification, reference being had to the accompanying drawing, forming part thereof.

In the drawing Fig. 1 is a plan view and Fig. 2 is an edge view of a badge or similar article showing our new design.

We claim:

The ornamental design for a badge or similar article, as shown.

JAMES G. AGNEW.
REED K. POND.
